DESIGN FOR A COTTON HARVESTING MACHINE

William N. Smith, Dallas, Tex.

Application October 1, 1945, Serial No. 122,415

Term of patent 14 years

(CL. D40—1)

To all whom it may concern:

Be it known that I, William N. Smith, a citizen of the United States, residing at Dallas, in the county of Dallas and State of Texas, have invented a new, original, and ornamental Design for a Cotton Harvesting Machine, of which the following is a specification, reference being had to the accompanying drawing, forming part thereof.

Figure 1 is a front elevational view of a cotton harvesting machine showing my new design.

Figure 2 is a perspective view thereof, and Figure 3 is a plan view of the cotton harvesting machine.

The dominant features of my design reside in the portions shown in full lines.

I claim:

The ornamental design for a cotton harvesting machine, as shown and described.

WILLIAM N. SMITH.
